UNITED STATES PATENT OFFICE.

JOHN B. HACKENDAHL, OF BEECHVIEW, PENNSYLVANIA.

STAMPING DEVICE.

1,333,487.

Specification of Letters Patent.

Patented Mar. 9, 1920.

Application filed October 3, 1919. Serial No. 328,099.

To all whom it may concern:

Be it known that I, JOHN B. HACKENDAHL, a citizen of the United States, residing at Beechview, in the county of Allegheny and State of Pennsylvania, have invented new and useful Improvements in Stamping Devices, of which the following is a specification.

This invention relates to a stamping device and has for its primary object to provide a self inking stamp of simple, inexpensive construction wherein the inking pad will be continuously held in engagement with the stamp when in normal position thereby insuring the proper inking of the stamp and besides preventing exposure of the inking surface of the pad to the atmosphere.

An object of the invention is to provide a simple construction of few parts for moving the inking pad to a non-interfering position when the stamp is in stamping position.

With these and other objects in view the invention will be better understood from the following detailed description taken in connection with the accompanying drawing wherein:

Figure 1 is a side elevation of the device in normal position.

Fig. 2 is a side elevation in stamping position.

Fig. 3 is a detailed sectional view on the line 3—3 of Fig. 1.

Again referring to the drawing illustrating one of the many forms in which my invention may be constructed, the numeral 1 designates a base provided with upstanding ears 2 and 3. The ears 2 are pivotally connected to an arm 4 hereinafter known as the pad arm. The ears 3 are pivotally connected to an arm 5 hereinafter known as the stamp arm. A spring 6 has one end connected to the arm 4 and the other end connected to the base acting in a manner to hold the arms 4 and 5 in a vertical position as shown in Fig. 1. The upper end of the arm 4 has connected thereto an inking pad 7 while the upper end of the arm 5 has fixed thereto a handle 8 that is in turn connected to a stamp 9; arranged so that it will continuously engage and cover the inking surface

of the pad 7 when the parts are in normal position.

For the purpose of controlling the relative movement of the arms when moving toward stamping position, I provide a link 10 pivotally connected at its ends to the arms with a result that when pressure is applied to the handle 8 both arms are moved but the relative movement will be regulated so that the pad 7 will move to non-obstructing position when the stamp 9 is in stamping position. To facilitate the coöperation of the arms, the arm 5 is provided with a slot 11 through which moves the arm 4.

From the foregoing description taken in connection with the accompanying drawing, it should be apparent that I provide a device of simple, inexpensive construction wherein upon return of the stamp to normal position the surface thereof will be immediately inked so that complete printing will be assured when the stamp is thrown to stamping position. It is of course to be understood that the parts may be constructed in other manners and associated in other relations and therefore I do not desire to be limited in any manner except as set forth in the claims hereunto appended.

Having described my invention, what I claim is—

1. A stamping device comprising an inking pad, a stamping element including a handle, a pair of arms crossing each other at an angle, one connected to said handle and the other to said pad, a base pivotally supporting the arms, a spring acting against one of the arms and a link connecting the arms together for the purpose set forth.

2. In a stamping device, a base, two arms pivoted at their lower ends to the base and crossing each other intermediate their ends when raised, an inking pad secured to the upper end of one of said arms, a stamp carried on the other arm and positioned to contact with said pad when the arms are raised, a link connecting said arms adjacent their upper ends, and means for normally holding the arms raised so as to hold the stamp and pad in contact with each other.

In testimony whereof I affix my signature.

JOHN B. HACKENDAHL.
